UNITED STATES PATENT OFFICE.

JAMES NOVY, OF MUSKOGEE, OKLAHOMA.

ROTARY VENTILATOR.

Application filed September 6, 1922. Serial No. 586,474.

To all whom it may concern:

Be it known that I, JAMES NOVY, a citizen of the United States, residing at Muskogee, in the county of Muskogee and State of Oklahoma, have invented new and useful Improvements in Rotary Ventilators, of which the following is a specification.

This invention relates to certain new and useful improvements in rotary ventilators, and has for its objects to provide, first, a continuously lubricated bearing for the revolving cowl, hood or head; second, to provide a bearing which is protected from all injurious gases and temperatures; third, to provide an inexpensive and easily replaceable bearing; fourth, to provide as noiseless a ventilator as possible by the use of a long guide for the supporting shaft, and one which is well braced and adjustable for correct alinement; and, finally, to provide a rotary ventilator which is strong and durable and designed for long and efficient service and free from parts liable to be broken or damaged or to easily get out of order.

The invention consists of the features of construction, combination and arrangement of parts, hereinafter fully described and claimed, reference being had to the accompanying drawings, in which:—

Figure 1 is a central vertical longitudinal section through a ventilator embodying my invention.

Figure 2 is a top plan view of the base section thereof showing the internal bearing means in section taken substantially on line 2—2 of Figure 1.

Figure 3 is a sectional plan view on the plane indicated by the line 3—3 of Figure 1, showing the fire-damper in closed position.

Figure 4 is a sectional elevation of the shaft bearing housing and bearing and end of the shaft journaled therein.

In the practical embodiment of my invention, as herein disclosed, I provide a rotary ventilator comprising a cylindrical stationary base section 1 and a rotary head, cowl or hood section 2, the latter being cylindrical at its base and having its lower edge arranged to surround and overlap the upper edge of the base section 1. These lapping edges of the sections 1 and 2 are reinforced by annular channel-iron braces 3. The head section 2 is provided with the usual side mouth or opening 4 and has disposed therein bracing members 5 and 6. Suitably at-

tached to the head section is the vane 7 adapting said head section to be rotated by currents of air striking against the vane, which turns to a point of least resistance. 60

Secured at its upper end to the head section 2 and extending downwardly through the bracing members 5 and 6 is a stationary shaft 8 having a tapered lower end 9 terminating in a hardened conical journal 10. 65 The said portion 9 of the shaft is received and turns within a bearing housing 11 consisting of a six-way pipe fitting having upper and lower openings 12 and 13 and side openings 14. The lower opening 13 is closed 70 in a fluid tight manner by a threaded plug 15 carrying an eye 16 and formed in its upper portion with a conical cavity 17 receiving a conical centering point 18 on a hardened metal bearing plate or disk 19 75 provided with a conical bearing recess 20 receiving the conical end journal 10 of the shaft 8. The lower end of the shaft thus turns in contact with a durable type of bearing which will last for a long period and 80 which, by simply detaching the plug 15, may be removed when worn to any extent and to admit of another bearing plate being substituted in its place.

The bearing housing 11 forms part of a 85 combined bearing, bracing and suspension frame structure supported by the base section 1. This structure includes, in addition to said housing 11, an annular series of supporting and bracing arms 21 arranged at an 90 angle of 90° to each other and threaded at their inner ends in the openings 14 and fitted at their outer ends in sockets 22 on the stationary base section 1. Threaded into the top opening 12 of the housing 11 is the 95 lower end of an upright supporting tube or pipe 23 which is connected at its upper end with a multi-armed bracing head 24. This head 24 consists, like the housing 11, of a six-way pipe fitting having top and bottom 100 openings 25 and 26 and an annular series of four side openings 27. The upper end of the pipe 23 is threaded into the lower opening 26 and supports the head 24 in position. The shaft 8 extends downwardly through 105 the head 24 and pipe 23 into the housing 11, which parts form a long bearing for the lower end of the shaft, whereby said shaft is held centered in position and prevented from tilting or wobbling or getting out of 110 proper alinement.

Connecting arms 28, which may consist of

ordinary pipe elbows, are threaded at their inner ends in the openings 27 and closed at their outer ends by plugs 29 provided with eyes 30. These eyes 30 receive the hooked 5 upper ends of rods 31 adjustably connected by turn buckles 32 to the upper ends of similar rods 33 having hooks at their lower ends engaging eyes 34 of plugs 35 closing the angle openings or sockets 36 of Y fittings 37, the sleeve portions of which are fitted upon the ends of the bracing arms 21. By this construction the pipe 23 and 10 bracing head 24 are coupled to and reinforced from the bracing arms 21 by an annular series of inclined stays which hold 15 the said portions 23 and 24 from lateral deflection. By means of these inclined stays, which are adjustable as described, the bracing head 24 may be laterally adjusted in any 20 direction as occasion may require to properly center the bracing and bearing structure and the shaft 8, whereby the shaft will be held from displacement under pressures exerted 25 upon the head section 2 and will maintain said head section in proper position, the centering of the shaft adapting it to work truly in its bearing against any tendency to bind, so that at all times an easy and accurate motion of the head section is ensured. 30 The construction described not only provides a firm and durable support for the shaft and head section, but the hollow parts of the bearing and brace frame structure particularly parts 11, 23 and 24, provide a 35 reservoir for oil or other lubricant, which may be introduced therewith as required by removal of one of the upper plugs 29. This oil will be confined in the bearing housing 11, and the bearing parts of the shaft will 40 thus be constantly immersed in oil, keeping them cool and reducing wear and tear to a material degree, the life of the working parts thus being materially prolonged and in addition said parts are thereby protected 45 from rust and disintegration from the action of the elements. For the purpose of reducing the amount of oil required, the inner ends of the pipes 21 may be closed at the point where they enter the openings 14, thus 50 confining the oil within a reservoir portions including the housing 11 and more or less of the upright bearing thereabove. The shaft end by being thus enclosed is at the same time protected from all injurious gases 55 and temperatures and an inexpensive and easily replaceable bearing provided therefor, which bearing and which structure in general ensures the production of a ventilator having a rotating part which will operate 60 easily and in a practically noiseless manner the long shaft bearing and continual lubrication of the bearing surfaces proper reducing friction to a minimum. 65 Arranged within the bottom of the station- ary base section 1 is a channelled bracing

ring 39, and formed at diametrically opposite sides of said section 1, adjacent to said ring 39, are bearing sockets 40 receiving the ends of a transverse rod or shaft 41. To this shaft are hinged the semi-circular sections 42 of a folding fire door, the sections of which are adapted when in closed position to rest upon the bracing ring 39, which forms a seat therefor. At their outer peripheral edges the door sections 42 are reinforced by angle irons 43 and carry weights 44 which adapt said door sections, when released for closing movement, to drop by gravity and seat upon the bracing ring 39. Secured to the outer edges of the door sections are end portions of chains or cables 45, which chains or cables pass in opposite directions over pulleys or sheaves carried in a suspension block 46 provided with a hook 47 engaging the eye 16 of the plug 15, whereby said suspension block is supported from the bracing and bearing frame. The other ends of the chains or cables 45 extend downwardly through slots 48 in the door sections and are connected by a fusible link 49 with a counterbalancing weight 50. This weight 50 normally counterbalances the door closing weights 44 and holds the door sections in the open position shown in Figure 1, thus normally leaving the ventilator shaft open for free ventilation. In the event, however, of the breaking out of a fire the passage of the hot smoke or gases through the ventilator will cause the link 49 to be fused or melted, thus freeing the weight 50 which will drop down and also freeing the chains or cables 45, thus allowing the door sections 42 to immediately drop by gravity down against the seat 39 and closing the ventilator shaft. 100

From the foregoing description, taken in connection with the accompanying drawings, the construction and mode of operation of my improved rotary ventilator will be readily understood, and it will be seen that the invention provides a device of this character which is simple of construction and which is long lived and hence durable and economical in operation. Also it will be seen that it provides a means for keeping the shaft constantly lubricated in a lengthened and braced bearing, which supports the shaft accurately in position and thus obviates liability of binding of the shaft or other derangement of the rotating parts. 110 Furthermore it will be seen that it provides a construction in which the bearing parts are protected from destructive gases and temperatures, in which an easily replaceable hardened bearing is furnished, which may be renewed in a convenient manner when occasion requires, which further provides for adjustment of an efficient type of bracing means whereby the bearing may at all 115 times be kept centered, thus adapting the ro- 120 125 130

tary head to operate in a practically noiseless manner, and which still further provides a door or damper adapted to automatically close the shaft upon the breaking out of a fire. These and other advantages of the invention will be understood and readily appreciated by those versed in the art without a further and extended description.

Having thus fully described my invention, I claim:—

1. In a rotary ventilator, the combination of a stationary base section, a rotary head section, a six-armed bearing housing in the base section, a six-armed bracing head enclosed within the head section above and in vertical alinement with said bearing housing, a tubular shaft guide connecting the upper vertical arm of the bearing housing with the lower vertical arm of the bracing head, radial braces connecting the horizontal arms of the bearing housing with the base section at angles of 90° to each other, bracing members connecting the correspondingly arranged arms of the bracing head with said radial braces extending from the bearing housing, adjusting connections in said arms, and a shaft carried by the head section and extending downwardly through the bracing head and shaft guide into said bearing housing.

2. In a rotary ventilator, the combination of a stationary base section provided with sockets, a rotary head section, a six-armed bearing housing in the base section, radial supporting and bracing arms arranged at angles of 90° to each other and connecting the horizontal arms of the bearing housing with the sockets of the stationary base section, sleeves on said arms, a six-armed bracing head arranged in the head section in vertical alinement with said bearing housing, a tubular shaft guide extending between the upper vertical arm of the bearing housing and lower vertical arm of the bracing head, braces extending between the correspondingly arranged arms of the bracing head and the radial arms of the bearing

head and connected with the sleeves of the latter, adjusting connections in the lengths 50 of said arms, and a shaft carried by the head section and extending downwardly through the bearing head and shaft guide and into said bearing housing.

3. In a rotary ventilator, the combination 55 of a stationary base section, provided with sockets a rotary head section, a hollow bearing housing in the base section, arms radiating from said housing and engaging the sleeves of the base section, sleeves on said 60 arms, a bearing member in said housing, a multi-armed bracing head in the head section, a hollow upright brace member connecting said head with the bearing housing, bracing members extending between 65 the arms of said bracing head and the sleeves of the aforesaid bracing arms, and a shaft carrying the head section and extending downwardly through the bracing head, hollow upright brace member and into the 70 bearing housing and turning in contact with the bearing therein.

4. In a rotary ventilator, the combination 75 of a stationary base section provided with sockets, a rotary head section, a hollow bearing housing in the base section, radial supporting and bracing arms extending therefrom and engaging the sockets of said base section, a bearing member in said housing, a multi-armed bracing head in the head section, an upright shaft guide between said 80 bearing housing and bracing head, sleeves upon the said radial supporting and bracing arms an annular series of, bracing members extending between the arms of the bracing 85 head and the sleeves on the supporting and bracing arms, turnbuckles in said bracing members for adjusting the same, and a shaft carrying the rotary head section and extending downwardly through the bracing 90 head and upright shaft support and into the bearing housing and turning in contact with the bearing member in said bearing housing.

In testimony whereof I affix my signature.

JAMES NOVY.
